UNITED STATES PATENT OFFICE.

LEON F. HOFFMAN, OF FRANKLIN, PENNSYLVANIA, ASSIGNOR TO CHICAGO PNEUMATIC TOOL COMPANY, OF NEW YORK, N. Y., A CORPORATION OF NEW JERSEY.

VALVE PROTECTOR.

Application filed June 6, 1921. Serial No. 475,517.

To all whom it may concern:

Be it known that I, LEON F. HOFFMAN, citizen of the United States, residing at Franklin, in the county of Venango and 5 State of Pennsylvania, have invented certain new and useful Improvements in Valve Protectors, of which the following is a specification.

The object, construction and utility of 10 this invention are herein set forth with sufficient clearness to enable those skilled in the art to which it relates, to make and use the same.

One type of valve that is extensively used 15 as an inlet and discharge valve in the cylinders of air compressors, is known as a "plate valve", in which the valve proper consists of an annulus of thin metal. This annular type of valve is yieldably retained upon its 20 seat by a compression spring composed of a thin sheet steel, coiled flat into volute form.

Heretofore, these springs have been associated with the valve in such a manner that the edge of the metal comprising the spring 25 was in direct contact with the valve, and in time, would wear a hole through the valve and destroy its utility.

It is the object of this invention to provide means whereby such detrimental action 30 of springs upon said type of valve as well as other types, may be wholly obviated.

The following specification, together with the accompanying drawings, clearly describe this invention.

35 In said drawings:

Fig. 1 is an enlarged elevation of a valve spring, with the valve protector, and the adjacent portion of the valve and the associated organization shown in section.

40 Fig. 2 is a plan view of the valve spring.

Fig. 3 is a plan view of the small end of a valve spring showing the position which the prongs of one form of valve protector occupy therein.

45 Fig. 4 is an elevation of an inlet valve for air compressors equipped with my improved valve protectors.

Fig. 5 is an elevation of the form of protector shown in Figs. 1 and 4.

50 Figs. 6 and 7 are elevations of modified forms of valve protectors and

Figs. 8, 9 and 10 are inverted plan views respectively of the forms shown in Figs. 5, 6 and 7.

Fig. 11 is a partial plan view of still another modified form of my invention.

The construction illustrated in the drawings is as follows:

Referring to Fig. 1, the plate valve is indicated by the numeral 1; 2 is the valve spring; 3 is the valve protector; 4 is the valve seat; and 5 is the valve keeper.

As will be plainly seen from Fig. 1, the spring to which my valve protector is applied is constructed of flat material, flat-wound, in volute, conical form. The larger end of said spring fits closely within the socket in the valve-keeper 5 and is thereby secured in its proper working condition. Each coil of said spring is overlapped by the adjacent larger coil and the spring is thus self-guiding; the small end of the spring 2 is in juxtaposition to the valve 1, and heretofore, as previously stated, has been employed in direct contact therewith, and in this practice it has resulted that this spring will wear a hole through the valve, thus necessitating its replacement.

For the purpose of obviating this wear upon the valve, I interpose between the adjacent faces of said valve and said spring, a protective device 3 of any suitable form as shown in Figs. 1 and 4. Owing to the greatly increased area of bearing surface which this device presents to the valve, as compared to the thin edge of the spring, as heretofore practiced, wear of the valve is practically eliminated.

By a reference to Fig. 2 it will be noted that the end of the material from which the spring is formed presents an inwardly projecting tang 6. While this tang is merely incidental, and a manufacturing expedient, it is common to nearly all flat-coiled, volute springs, and the preferred forms of my invention are made to conform thereto; thus the reason for certain features of these forms becomes clearly apparent.

Referring to the protector 3 as shown in elevation in Figs. 1, 4, 5 and in inverted plan in Fig. 8, this consists of a metal disc or plate 7 from which approximately radial sections are cut and turned perpendicularly to the face of the plate to form the prongs 8. In using this form of protector, said prongs are inserted within the spring so that they occupy the position shown in Fig. 3. It will be seen that the tang 6 does

not interfere with the insertion and use of this form of protector.

A modified form of protector is shown in section in Fig. 6 and in inverted plan in Fig. 9. This form consists of a disc 9 having its central portion punched outwardly to form a tubular boss or projection 10 to enter the opening of the spring, and slots 11 are cut in said boss to provide for the reception of said tang 6, thus an outwardly-projecting flange is formed at the valve-contact point of the spring.

Another modified form of protector is shown in elevation in Fig. 7 and in inverted plan in Fig. 10. This may be a device turned from solid metal, consisting of the plate or flange 12 with a boss 13 to enter the opening of the spring. Slot 14 is for the reception of said tang 6.

Fig. 11 is a partial plan view in which the upper edge of the spring itself is formed into an annular, outwardly-projecting integral flange 15, which serves, as do the other forms, to increase the normal bearing area for the spring upon the valve.

I am aware that valve-springs have been provided with "guide-plungers" which serve to keep the spring in position and reduce the possibility of its coils contacting with the edges of the socket in which the spring is mounted. I am also aware that plate valve springs have been provided with "guide-shoes" and "thimbles" which operate in the spring-sockets and serve to guide the movement of the valve and to receive the operative wear. I am further aware that plate valves have been held upon their seats by a series of hollow plungers containing compression springs, said hollow plungers being connected to the valve so as to retain it in its proper operative position. I am still further aware that a suitably-formed plate has been used between the end of a compression spring and a valve with

which said spring cooperates for the purpose of keeping said spring positioned concentrically with the valve. I specifically disclaim such constructions and uses because my spring and the valve protector associated therewith differ from such constructions and uses in the following respects:

1. My spring being formed of flat material, flat-wound in volute conical form with each coil overlapped by the adjacent, larger coil and with the smaller end of the spring adjacent to the valve, and its larger end fitting closely into the socket of the keeper, it is self-guiding, hence is in need of no plunger or like element to prevent its coils from contacting with the edges of the socket which it occupies.

2. My protective device has no cooperative relation to the socket in which its spring is mounted.

3. My valve is not retained in position either by my spring or by the valve protector.

4. My protector is not used for the purpose of keeping the end of the spring with which it is associated in a given relation to the valve.

I claim the following:

In a valve organization, in combination, a valve seat, a valve keeper, a valve of the plate type intermediate said seat and said keeper, springs formed of flat material, flat wound in volute conical form, the larger ends of which seat in sockets in said keeper, the smaller or tang ends being adjacent said valve, and protectors for said valve interposed between said valve and said springs, said protectors being of flat sheet material with struck up parts engaging the interior of said springs and providing spaces for the tang ends thereof.

In testimony whereof I affix my signature.

LEON F. HOFFMAN.
